UNITED STATES PATENT OFFICE.

NEIL JEFFERSON BAGGETT, OF GUNSMITH, TEXAS.

COTTON-CHOPPER.

SPECIFICATION forming part of Letters Patent No. 452,093, dated May 12, 1891.

Application filed January 26, 1891. Serial No. 379,077. (No model.)

To all whom it may concern:

Be it known that I, NEIL JEFFERSON BAGGETT, a citizen of the United States, residing at Gunsight, in the county of Stephens and State of Texas, have invented certain new and useful Improvements in Cotton-Choppers; and I do hereby declare the following to be a full, clear, and exact description of the invention, such as will enable others skilled in the art to which it appertains to make and use the same.

My invention relates to a cotton-chopper; and the object of my invention is to provide a machine that is simple in construction and thoroughly effective in operation. I attain said object by a certain construction, combination, and arrangement of parts fully described in this specification and illustrated in the accompanying drawings, in which—

20 Figure 1 is a front view of the invention. Fig. 2 is a plan view of the same. Fig. 3 is a perspective view of the axle and adjustable frame and chopper detached from the wheels. Fig. 4 is a detailed view of the saddle and 25 crank-shaft.

Referring to the drawings, the letter A designates the axle, which is constructed with the slots or reduced portions *a* upon each side and in the center of same. Said slots are 30 adapted to receive the adjustable staple-shaped frame or saddle B. It will be observed that the transverse bar or rod C passes through the top of this frame and projects upon each side through the slots *d d'* in the top of the 35 choppers D D', thereby holding said choppers securely in their normal positions and at the same time allowing them a free vertical movement. In the lower ends of the staple-shaped frame or saddle B there are the slots *b*, having 40 the transverse bolts *b'*, which afford a bearing for the crank-shaft E. The ends of the crank-shaft E are rigidly secured near the shank to the front and rear portions of the choppers D and D', respectively, by means of the screw- 45 eyebolts F. These screw-eyebolts may be located in any part of the slot *f* of the choppers D and D', accordingly as it is desired to regulate the depth of the chopping. When shallow chopping is needed the screw-eyebolts F 50 are placed in the topmost portion of the slot *f*, and vice versa when it is desired to have the plates G of the choppers penetrate deeply.

Upon the front or rear portions of the crank-shaft E there is located and rigidly secured a sprocket-wheel H, which drives the crank-shaft E. It is easily seen that the staple-shaped frame B, to which is attached the choppers D and D', can be easily removed or detached from the axle A simply by removing the bolts *b'* and raising the same vertically 60 from off said axle.

I represents the *n*-shaped frame, which is secured horizontally across the axle A by means of a *T*-shaped screw-bolt *i*, which is located in a longitudinal slot in the axle A. In 65 the lower ends of said frame I there are suitable bearings *i'*, in which is located the shaft J, having upon each end the pinion K. Upon the shaft J there is also located a sprocket-wheel L.

M indicates a crown-wheel, which is rigidly attached to one of the ground-wheels N of the machine.

O is a sprocket-chain that connects the sprocket-wheels H and L, respectively.

The machine may be readily thrown out of gear simply by loosening the *T*-shaped screw-bolt *i* and slipping the *n*-shaped frame toward the center of the axle A and then tightening said bolt.

P is a guard to protect the end of the rod C, and serves as a support for the handle R in raising the choppers D D'.

S is a tension-wheel for tightening the sprocket H.

It is well to mention the fact that the mechanism of my chopper, as herein described, can be applied to almost any two-wheeled cultivator by making a few slight alterations, which will readily suggest themselves to any 90 person of ordinary mechanical skill.

The operation of my machine is as follows: The wheels N impart motion to the crown-wheel M, which in turn communicates motion to the pinions K of the shaft J, which drives 95 the sprocket-wheels H and L. The sprocket-wheel H imparts motion to the crank-shaft E, which drives the vertical choppers.

As it is apparent that my invention is both useful and practical, I deem it useless to further enlarge upon its merits.

What I claim is—

1. In a cotton chopper or cultivator, the axle mounted upon suitable ground-wheels,

in combination with a crown-wheel rigidly secured to one of said ground-wheels, the n-shaped frame secured horizontally across the axle near the inner side of one of the ground-wheels, the shaft J, having bearings in the lower ends of said frame and provided with pinions and sprocket-wheel L, the adjustable staple-shaped frame or saddle fitting over the center axle of the machine, the transverse bar passing through the top of this frame and projecting through the slots in the top of the choppers D and D', the crank-shaft E, having bearings in the lower end of said staple-shaped frame and having its ends located in the screw-eyebolts upon the front and rear sides of the choppers D and D', the sprocket-wheel H, rigidly secured upon said crank-shaft, the vertical choppers D and D', operated by the crank-shaft E, and the sprocket-chain connecting the sprocket-wheels H and L, all substantially as described, and for the purpose set forth.

2. In combination with the co-operating mechanism of a cultivator or cotton-chopper, the adjustable staple-shaped frame or saddle B, the transverse bar C, passing through the top of this frame and the slots in the top of the choppers D and D', the crank-shaft E, having bearings in the lower end of the frame B and having its ends located in the screw-eyebolts upon the front and rear sides of the choppers D and D', the sprocket-wheel H, rigidly secured upon said crank-shaft, and the vertical choppers D and D', substantially as described, and for the purpose set forth.

In testimony whereof I affix my signature in presence of two witnesses.

NEIL JEFFERSON BAGGETT.
